UNITED STATES PATENT OFFICE.

ALICE M. AIKEN, OF CLEVELAND, OHIO.

DESIGN FOR A SANITARY PROTECTOR.

45,443.

Specification for Design.

Patented Mar. 24, 1914.

Application filed November 11, 1912. Serial No. 730,816. Term of patent 14 years.

To all whom it may concern:

Be it known that I, ALICE M. AIKEN, a citizen of the United States, residing at Cleveland, county of Cuyahoga, and State of Ohio, have invented a new, original, and ornamental Design for Sanitary Protectors, of which the following is a specification, reference being had to the accompanying drawing, forming part thereof.

The figure is a rear elevation of a sanitary protector showing my new design.

I claim—

The ornamental design for a sanitary protector as shown.

ALICE M. AIKEN.

In the presence of—

H. O. YODER,

Wm. M. MONROE.

Copies of this patent may be obtained for five cents each, by addressing the "Commissioner of Patents, Washington, D. C."
